ORIENTING APPARATUS FOR WELLS

Ralph Warren, Houston, Tex., assignor, by mesne assignments, to Houston Oil Field Material Company, Inc., a corporation of Texas

Application October 21, 1940, Serial No. 362,079

2 Claims. (Cl. 255—1.6)

The invention relates to an orienting apparatus for wells wherein it is desired to orient the drill stem in deflecting or other operations.

It is one of the objects of the invention to provide an apparatus which can be turned in the well bore and create a signal at the surface so that the operator will be advised that the tool is oriented in the well bore.

Another object of the invention is to provide an orienting apparatus for drill stems which will release an accumulated pressure so as to signal the operator at the surface.

Another object of the invention is to provide a signaling apparatus which can be so adjusted prior to lowering into the well bore so that a ball will move by gravity to the low side of the hole and indicate at the surface that the drill stem has been oriented.

Another object of the invention is to provide an orienting apparatus which can be made inactive by the pressure of the drilling mud through the drill stem after it has served its purpose of orienting the drill pipe.

Other and further objects of the invention will be readily apparent when the following description is considered in connection with the accompanying drawing herein:

Figure 1 is the side elevation of a section of drilling pipe with certain parts shown in section and illustrating the orienting instrument as carried by the drill pipe.

Figure 2 is a section taken on the line 2—2 of Figure 1.

Figure 3 is a vertical sectional view of the orienting instrument.

Figure 4 is a wiring diagram of the releasing connection for the orienting instrument.

In the drilling of well bores it is often desirable to deflect the well bore in a predetermined or desired direction so as to penetrate a productive formation. In other instances it is desirable to correct the inclination of a well bore where it has deviated from the vertical or from the desired direction. In both of the above instances a deflecting tool or a whipstock is lowered into the well bore and oriented so as to continue the drilling in the desired direction. Most often the drilling is to continue along an inclination or at an angle with respect to the inclination of the well bore. This predetermined or desired direction is usually known to the operator and its orientation or relationship with respect to the low side of the hole is also known, and with this information at hand the present invention contemplates that the instrument may be adjusted so that the

drilling or deflecting of the hole will occur at the desired oriented direction of the hole as a zero.

The equipment by which the invention is carried out is best seen in Figures 1 and 3, wherein 5 2 represents a drill stem section and 3 a drill collar or another drill stem section. A drill sub, 4, is shown as having been threaded between the sections 2 and 3 and this sub is specially constructed to provide a restricted neck or orifice 6 adjacent its upper end. Fixed in the passage or chamber 7 in the sub 4 is an orienting instrument 9 which is held in place by a bracket or arm 10. This arm is best seen in section in Figure 2 15, where it is held in position by a set screw 11.

The instrument 9 is seen in section in Figure 3 and includes the lower or base portion 15, and the head 16 which is slidably mounted on the reduced area 17. At the upper end of the base 15, the 20 head 16 is held against sliding movement by a latch mechanism 18 disposed in the chamber 19 in the head. A groove 20 in the chamber 19 receives the ends of 21 of the levers 22 which are pivoted at 23 on a block 24 on the upper end of the portion 17. The links 25 are pivoted to a core 26 so that movement of the core 26 retracts and extends the ends 21 relative to the groove 20. A spring 27 normally supports the head 16 in extended position above the base 15.

30 As seen in Figure 1, the head 16 is of a size to fit snugly within the restriction 6 so that drilling mud passing down through the drill stem will be forced into the cup portion 30 and the bypass 31 so as to flow into the chamber 7 and on downwardly to the drill bit.

It is desirable to build up a pressure in the drill stem 2 above the orienting instrument, and to this end a ball 32 will be dropped through the drill stem and be received in the cup 30. The 40 pressure can then be built up in the drilling stem by the pumps at the surface so that there will be a tendency to move the head 16 downwardly out of the restriction 6. The latch mechanism 18, however, prevents the downward movement of the head and as long as the pressure builds up in the drill stem the operator at the surface is aware of the fact that his drill stem has not been oriented.

In order to release the orienting mechanism and 50 signal the operator by releasing the pressure in the drill stem, a contact mechanism has been provided in the base 15. This includes an electrical circuit seen in Figure 4 at 40, wherein the battery 41 in the circuit is connected to a contact 42 on one side of the circuit and to a

solenoid coil 43 in the other side of the circuit which in turn terminates from the contact 44. The coil 43 encloses the solenoid core 26. A metal ball 47 is arranged to close the circuit by engaging the contacts 42 and 44 so as to energize the coil 43 and exert a downward pull on the core 26. The parts thus described are seen in Figure 3 wherein the contact 42 forms the base of a cup 48 and the wall of the cup carries the contact 44. The cup 48 is adjustably mounted in the base 10 and can be fixed in position by a set screw 49.

When the operator desires to lower the device into the well he will set the instrument inside of the sub 4 with the cup 48 so adjusted that he is aware that the orientation of the contact 44 15 with respect to the direction of the inclination of deflection of the whipstock, or deflecting tool as the case may be, which is connected with the lower end of the drill section 3.

Thus if the operator desires to deflect the well at an angle of 90 degrees from the lower side of the hole, he will set the cup 48 in such an angular relationship with respect to the face of the whipstock or the direction of the deflecting tool so that when the contact is at the low side of the hole the face or direction of the deflecting tool will be 90 degrees therefrom and at the desired azimuth.

With the parts adjusted as directed, the drill stem will be lowered into the well bore without regard to its oriented or rotated position. If the well is to be washed or circulation established the drilling mud can be pumped through the bypass 31. When it is desired then to orient the tool, the ball 32 will be dropped into position to close the drill stem. The drill stem can now be turned slowly while the pump pressure is maintained. The ball 47 will roll along the low side of the cup 48 as the drill stem is turned. When the contact 44 moves around underneath the low side of the ball 47, the circuit 40 will be closed as the ball is riding on the contact 42. When the circuit 40 is thus closed, the coil 43 is energized, the core 26 moved down and the latch 18 released. The pump pressure in the drill stem now moves the head 16 downwardly to open the restriction 6. This releases the pressure in the drill stem and the operator observes this release at the surface. This release of pressure indicates to him that the contact 44 is now at the low side of the hole and that the whipstock or deflecting tool is turned in the desired direction.

The head 16, having moved out of the restriction 6, no longer serves as an obstruction to the flow of the drilling mud and the deflecting operation can proceed as desired.

5 While the instrument is shown as fixed in the pipe prior to being lowered into the well it seems obvious that a suitable seat or trackway could be provided in the pipe and a complementary portion on the instrument so that the instrument may be lowered, dropped or pumped through the pipe to such seat when an orientation was desired.

Broadly, the invention contemplates an automatic orienting device for drilling tools.

What is claimed is:

1. An orienting sub for a string of drill pipe having a fluid circulation passage forming a portion of the fluid passage of the drill string, means to restrict the flow of fluid in said passage, said 20 restriction means being movable to a substantially non-restricting position, latch means to normally hold said restriction means in restricting position, latch releasing means to release said restriction means for movement into non-restricting position, and gravity responsive means 25 constructed to actuate said latch release means when the gravity responsive means is at any set angular position relative to some significant part of the drill stem.

30 2. An orienting sub for a string of drill pipe having a fluid circulation passage forming a portion of the fluid passage of the drill string, means to restrict the flow of fluid in said passage, said restriction means being movable to a substantially non-restricting position, latch means to normally hold said restriction means in restricting position, latch releasing means to release said restriction means for movement into non-restricting position, gravity responsive means 35 constructed to actuate said latch release means when the gravity responsive means is at any set angular position relative to some significant part of the drill stem, and additional means to close said restricting means against flow therethrough during the orienting of the sub so that actuation of 40 said latch to release said restricting means opens the passage and the release of fluid for flow through the passage can be observed as an indication that the sub is oriented.

45 3. An orienting sub for a string of drill pipe having a fluid circulation passage forming a portion of the fluid passage of the drill string, means to restrict the flow of fluid in said passage, said restriction means being movable to a substantially non-restricting position, latch means to normally hold said restriction means in restricting position, latch releasing means to release said restriction means for movement into non-restricting position, gravity responsive means 50 constructed to actuate said latch release means when the gravity responsive means is at any set angular position relative to some significant part of the drill stem, and additional means to close said restricting means against flow therethrough during the orienting of the sub so that actuation of said latch to release said restricting means opens the passage and the release of fluid for flow through the passage can be observed as an indication that the sub is oriented.

RALPH WARREN.
